(57) **CLAIM**

The ornamental design for a game controller, as shown and described.

DESCRIPTION

FIG. 1 is a front perspective view of the game controller showing our new design in an illuminated state;

FIG. 2 is a bottom view thereof;

FIG. 3 is a top view thereof;

FIG. 4 is a right side view thereof;

FIG. 5 is a left side view thereof;

FIG. 6 is a front view thereof;

FIG. 7 is a rear view thereof; and,

FIG. 8 is a rear perspective view thereof.

The broken line showing of the remainder of the controller is for the purpose of illustrating unclaimed portions and forms no part of the claimed design. The radiating lines emanating from the two ring-shaped regions represent illumination.
